HEATING DEVICE AND METHOD FOR OPERATING A HEATING DEVICE

FIELD

The present invention relates to a warm water reservoir, as well as to a method.

BACKGROUND INFORMATION

A conventional heating device, which includes at least one heating unit that is configured to heat at least one fluid, includes at least one fluid supply line, which is provided for supplying the fluid to the heating unit for heating, and at least one fluid discharge line, which is provided for discharging the fluid from the heating unit after the heating. The heating unit is operated in a pulsed manner with the aid of a control and/or regulating unit, in order to set a particular temperature.

SUMMARY

The present invention relates to a heating device, including at least one heating unit, which is configured to heat at least one fluid; at least one fluid supply line, which is provided for supplying the fluid to the heating unit for heating; at least one fluid discharge line, which is provided for discharging the fluid from the heating unit after the heating; and a control and/or regulating unit, which is configured to operate the heating unit in at least one operating state, in order to set a particular temperature.

It is provided that the heating device include a valve unit, which is configured to mix the fluid in the fluid discharge line with fluid from the fluid supply line, upstream from an outlet.

In this connection, a "heating device" is to be understood, in particular, as at least a part, in particular, a submodule of a heater, and preferably, of a continuous-flow heater. In particular, the heating device may also include the entire heater, and preferably, the entire continuous-flow heater. In this connection, a "heating unit" is to be understood, in particular, as a unit, which is configured to convert energy, in particular, electrical energy, bioenergy and/or, preferably, fossil energy into heat, in particular, directly, and to supply it, in particular, to a fluid, advantageously, water. In particular, the heating unit includes at least one heating module and, advantageously, at least one heat exchanger. In this context, the heating module may take the form of an electric heater and/or of, advantageously, a burner, in particular, an oil burner and, particularly preferably, a gas burner, and, advantageously, is thermally connected to the heat exchanger, in order to heat the fluid. The heat exchanger includes, in particular, at least one supply line for an, in particular, unheated fluid and/or fluid to be heated; and, in particular, at least one outlet for a fluid heated, in particular, by the heating module. In this connection, that the "heating unit is configured to heat a fluid" is to be understood to mean that in at least one operating state, the heating unit and, in particular, the heating module are configured to increase a temperature of the fluid by at least 5° C., advantageously, by at least 15° C., preferably, by at least 25° C., and, particularly preferably, by at least 35° C., in comparison with a reference temperature and/or an initial temperature. In particular, "configured" is to be understood as specially programmed, designed, and/or equipped. An object being provided for a certain function is to be understood to mean, in

particular, that the object fulfills and/or executes this particular function in at least one state of application and/or operating state.

In addition, a "control and/or regulating unit" is to be understood, in particular, as an electric and/or electronic unit having at least control electronics. "Control electronics" are to be understood, in particular, as a unit including an arithmetic unit, a storage unit, as well as an operating, control and/or regulating program, which is stored in the storage unit and is intended, in particular, to be executed by the arithmetic unit. In the at least one operating state, the control and/or regulating unit is advantageously configured to operate the heating module in a pulsed manner, using at least two pulses, in order to, in particular, set and/or adjust a certain temperature. The control and/or regulating unit being configured to "operate" the heating unit and/or the heating module "in a pulsed manner" should be understood to mean, in particular, that the control and/or regulating unit is configured to operate the heating unit and/or the heating module in a clocked manner and/or discontinuously, and/or to supply it/them with energy, in particular, electric current and/or, advantageously, fuel. The control and/or regulating unit is advantageously configured, in particular, in a pulsed operation, to operate the heating unit and/or the heating module in a first time interval; and, in a second interval, in particular, directly following the first interval in time, to reduce a heating power of the heating module, in particular, in comparison with the first interval; and/or to advantageously adjust an operation of, in particular, the heating unit and/or the heating module, in particular, completely; and/or to completely disconnect a power supply. A first time interval immediately follows the second time interval in an advantageous manner. In this context, a first time interval determines, in particular, a pulse duration of one pulse of the at least two pulses. In this connection, the expression "short-term" is to be understood as, in particular, a period of time of, at a maximum, 200 s, preferably, at a maximum, 100 s, and particularly preferably, at a maximum, 50 s.

In this connection, a "valve unit" is to be understood as, in particular, a unit, which is configured, in particular, to block and/or stop a flow of fluids. In particular, the valve unit includes at least one, in particular, electromotively actuated valve and/or at least one electromagnetically actuated valve. In particular, the valve unit is controllable by the control and/or regulating unit. In particular, a valve position of at least one valve of the valve unit may be changed via activation by the control and/or regulating unit. The valve unit is positioned, in particular, fluidically at least partially between a fluid supply line, which is provided for supplying the fluid to the heating unit for heating, and a fluid discharge line, which is provided for discharging the fluid from the heating unit after the heating. The valve unit being configured "to mix fluid in the fluid discharge line with fluid from the fluid supply line upstream from an outlet" is to be understood to mean, in particular, that as a function of a valve position, the valve unit directs a volumetric flow of the fluid from the fluid supply line to the fluid discharge line, in particular, to reduce a fluid temperature to a desired outlet temperature.

In addition, the heating device may include at least one sensor, in particular, a flow rate sensor and/or temperature sensor, which is provided, in particular, for measuring at least one measured variable correlated with the fluid, in particular, a flow rate and/or a temperature.

Using such a refinement, a generic heating device having improved operating characteristics may be provided. In particular, advantageous flexibility and/or advantageous

efficiency may be achieved, in particular, cost efficiency, weight efficiency and/or power efficiency. In addition, advantageously high temperature stability and/or advantageously flexible temperature adjustment may be rendered possible. Furthermore, comfort may be advantageously increased, in particular, for an end user; in particular, sudden temperature fluctuations being able to be minimized in an advantageous manner.

In addition, it is provided that the control and/or regulating unit be configured to control the valve unit in such a manner, that an at least substantially uniform outlet temperature of the fluid sets in. In this connection, the control and/or regulating unit being configured to control the valve unit in such a manner, that an at least substantially "uniform outlet temperature of the fluid sets in," is to be understood to mean, in particular, that the control and regulating unit is configured to set a rate of volumetric flow through the valve unit in such a manner, that an outlet temperature of the fluid having a fluctuation of a maximum of 3°C., advantageously, of a maximum of 2°C., and particularly preferably, of a maximum of 1°C., results. In this context, the control and/or regulating unit is advantageously configured to adjust a temperature of the fluid at, in particular, an outlet, at least substantially as desired, in a temperature range of 20°C. to 80°C., preferably, 30°C. to 70°C., and particularly preferably, 40°C. to 60°C. In this context, in particular, in the scope of an adjustment accuracy of the control and/or regulating unit, the expression "at least substantially as desired" is to be understood as arbitrarily. Through this, an outlet temperature may be set in an advantageously simple and/or reliable manner, with advantageously negligible temperature fluctuations.

In addition, it is provided that the control and/or regulating unit be configured to control the valve unit at least substantially synchronously with the pulsed operation of the heating unit. In this connection, "at least substantially synchronously" is to be understood to mean, in particular, that a control pulse generated and/or outputted by the control and/or regulating unit for controlling the heating unit is generated and/or outputted simultaneously to a control pulse for controlling the valve unit. In particular, the valve unit and the heating unit are controlled, using two at least substantially equal-frequency and synchronized, in particular, synchronous or oppositely directed control pulses. In this manner, advantageous synchronization of a pulsed operation of the heating unit and control of the valve unit may be achieved.

In addition, it is provided that the control and/or regulating unit be configured to increase a flow rate of fluid through the valve unit in response to increasing heating power of the heating unit, during the pulsed operation. In particular, in response to increasing heating power of the heating unit, the control and/or regulating unit is configured to increase a flow rate of fluid through the valve unit to such an extent, that an increase in an outlet temperature of the fluid above a setpoint temperature is offset at least substantially. Preferably, the control and/or regulating unit is further configured to reduce a flow rate of fluid through the valve unit during pulsed operation, in response to falling heating power of the heating unit. In particular, in response to falling heating power of the heating unit, the control and/or regulating unit is configured to reduce a flow rate of fluid through the valve unit to such an extent, that a decrease in the outlet temperature of the fluid below a set point temperature is at least substantially offset. In this manner, an outlet temperature of the fluid may advantageously be held constant.

In one preferred refinement of the present invention, it is provided that the valve unit include at least one bypass valve, which is situated fluidically in parallel with the heating unit. In this manner, a variable volumetric flow of a fluid may easily be directed from the fluid supply line to the fluid discharge line.

In one preferred refinement of the present invention, it is provided that the valve unit include at least one mixing valve, which is situated fluidically in the fluid discharge line. In this manner, fluid in the fluid discharge line may easily be mixed with a variable volumetric flow of a fluid from the fluid supply line in an advantageous manner.

In addition, it is provided that the control and/or regulating unit be configured to operate the heating unit in a pulsed manner, such that the fluid is heated to a temperature, which lies above a selected outlet temperature of the fluid. This advantageously allows a sufficiently high outlet temperature of the fluid to be obtained at any time.

Furthermore, a heater, in particular, continuous-flow heater, having at least one heating device according to the present invention, is provided. In this manner, a particularly flexible and/or efficient heater may be provided.

In addition, the present invention is directed to a method for operating a heating device including at least one heating unit, which is configured to heat at least one fluid; at least one fluid supply line, which is provided for supplying the fluid to the heating unit for heating; at least one fluid discharge line, which is provided for discharging the fluid from the heating unit after the heating; and a control and/or regulating unit, which is configured to operate the heating unit at least partially in a pulsed manner, in at least one operating state, in order to set a particular temperature; upstream from an outlet, the fluid in the fluid discharge line being mixed with fluid from the fluid supply line. This allows, in particular, a flexibility and/or an efficiency to be increased in an advantageous manner.

In this connection, the heating device of the present invention is not limited to the use and specific embodiment described above. In particular, the heating device of the present invention may include a number different from a number of individual elements, component parts and units mentioned here, in order to implement a method of functioning described here.

BRIEF DESCRIPTION OF THE DRAWINGS

Further advantages are derived from the description below of the figures. Two exemplary embodiments of the present invention are shown in figures. The figures and the description herein include numerous features in combination. One skilled in the art will advantageously consider the features individually, as well, and integrate them to form useful, further combinations.

FIG. 1 shows a schematic block diagram of a heater including a heating device.

FIG. 2 shows a graphical representation of temperature curves of the heating device and fluid flow rate curves of a valve unit.

FIG. 3 shows a schematic block diagram of a heater including an alternative heating device.

FIG. 4 shows a schematic block diagram of a heater including a further alternative heating device.

DETAILED DESCRIPTION OF EXAMPLE EMBODIMENTS

FIG. 1 shows a schematic block diagram representation of a heater 34a exemplarily taking the form of a continuous-

flow heater. Heater 34a includes a heating device 32a. Heating device 32a includes a heating unit 10a. Heating unit 10a is configured to heat a fluid. In the present case, heating unit 10a is configured to heat water. To that end, heating unit 10a includes a heating module 36a. Heating module 36a takes the form of a gas burner module. However, as an alternative, it is also conceivable for the heating unit to be configured to heat a different fluid, such as a refrigerant and/or a heating medium. Heating device 32a includes a fluid supply line 12a, which is provided for supplying the fluid to heating unit 10a for heating, and a fluid discharge line 14a, which is provided for discharging the fluid from heating unit 10a after the heating.

Heating module 36a includes a suction unit 38a, which is provided for drawing in combustion air and fuel. To that end, suction unit 38a is connected to a first supply line 40a for combustion air, and to a second supply line 42a for fuel. Heating module 36a further includes a burner 44a. A combustion-air/fuel mixture is supplied to burner 44a by suction unit 38a. Burner 44a is configured to burn the combustion-air/fuel mixture in at least one operating state. In this context, burner 44a is configured to produce a heating flame.

In addition, heating unit 10a includes a heat exchanger 46a. Heat exchanger 46a is situated in the vicinity of the heating flame. Heat exchanger 46a is configured to transfer thermal energy from heating module 36a to the fluid. An unheated fluid, in particular, water, is supplied to heat exchanger 46a via fluid supply line 12a. Heated fluid is directed out of heat exchanger 46a via fluid discharge line 14a.

Furthermore, heating unit 10a includes an exhaust gas module 48a. Exhaust gas module 48a takes the form of a chimney. Exhaust gas module 48a is provided for removing exhaust gases. To that end, exhaust gas module 48a is connected to an exhaust gas outlet 50a.

In addition, heating device 32a includes a supply unit 52a. Supply unit 52a is configured to supply the unheated fluid to heat exchanger 46a and/or heater 34a. To that end, supply unit 52a includes a fluid inlet 54a. Fluid inlet 54a is connected to fluid supply line 12a. In addition, supply unit 52a includes a main valve 68a, which is positioned in fluid supply line 12a. Furthermore, heating device 32a includes a discharge unit 56a. Discharge unit 56a is configured to remove the heated fluid from heat exchanger 46a and/or heater 34a. For that purpose, discharge unit 56a includes an outlet 20a, which is connected to fluid discharge line 14a.

Heating device 32a also includes a plurality of sensors 60a, 62a, 64a, 66a. A first sensor 60a takes the form of a flow rate sensor. A second sensor 62a takes the form of a first temperature sensor. Second sensor 62a is provided for detecting a temperature of the fluid directly downstream from fluid inlet 54a. A third sensor 64a takes the form of a second temperature sensor. Third sensor 64a is provided for detecting a temperature of the fluid directly downstream from heat exchanger 46a. A fourth sensor 66a takes the form of a third temperature sensor. Fourth sensor 66a is provided for detecting a temperature of the fluid directly upstream from outlet 20a.

In addition, heating device 32a includes a control and/or regulating unit 16a. Control and/or regulating unit 16a is configured to control an operation of heating device 32a. To that end, control and/or regulating unit 16a includes an arithmetic unit, a storage unit, and an operating program, which is stored in the storage unit and is configured to be executed by the arithmetic unit. In addition, control and/or regulating unit 16a is configured to set and/or supply the requested heating power. For that purpose, control and/or

regulating unit 16a has an electrical connection with sensors 60a, 62a, 64a, 66a. In addition, control and/or regulating unit 16a has an electrical connection with burner 44a and main valve 68a. Control and/or regulating unit 16a is configured to control burner 44a and main valve 68a. In one operating state, control and/or regulating unit 16a is configured to operate heating unit 10a, in particular, heating module 36a, in a pulsed manner, in order to set a particular temperature.

In addition, heating device 32a includes a valve unit 18a. Valve unit 18a is configured to mix the fluid in fluid discharge line 14a with fluid from fluid supply line 12a, upstream from outlet 20a. Valve unit 18a includes a bypass valve 28a, which is connected fluidically in parallel with heating unit 10a. First sensor 60a and main valve 68a are situated fluidically in back of a branching-off point 70a from fluid supply line 12a to a bypass line 72a connected to bypass valve 28a. Control and/or regulating unit 16a is configured to control valve unit 18a in such a manner, that a uniform outlet temperature 22a of the fluid sets in (cf. FIG. 2).

FIG. 2 shows a pulsed operating mode. In this context, a time is represented on an abscissa axis 74a. An ordinate axis 76a is represented as a magnitude axis. In the present case, in the operating state, control and/or regulating unit 16a is configured to operate heating module 36a in a pulsed manner, in order to set a particular temperature. Control and/or regulating unit 16a is configured to operate heating unit 10a in a pulsed manner, such that the fluid is heated to a temperature, which lies above a selected outlet temperature 22a of the fluid. A curve 78a indicates the periodically fluctuating temperature of the fluid immediately downstream from heat exchanger 46a, measured by third sensor 64a. The fluid in fluid discharge line 14a is mixed with fluid from fluid supply line 12a, directly upstream from outlet 20a. In this context, an inflow amount of the fluid from fluid supply line 12a is adjusted with the aid of valve unit 18a. A second curve 80a indicates the temperature of the fluid immediately downstream from fluid inlet 54a, measured by second sensor 62a. Control and/or regulating unit 16a is configured to control valve unit 18a at least substantially synchronously with the pulsed operation of heating unit 10a. Control and/or regulating unit 16a is configured to increase a flow rate of fluid 24a through valve unit 18a during pulsed operation, in response to increasing heating power of heating unit 10a, and to reduce flow rate of fluid 24a through valve unit 18a again, during pulsed operation, in response to decreasing heating power of heating unit 10a. A third curve 82a shows the flow rate of fluid 24a through valve unit 18a changing synchronously with the temperature of the fluid immediately downstream from heat exchanger 46a. A fourth curve 84a shows the resulting uniform outlet temperature 22a of the fluid by fourth sensor 66a.

Further exemplary embodiments of the present invention are shown in FIGS. 3 and 4. The following descriptions and the figures are mainly limited to the differences between the exemplary embodiments; regarding component parts labeled identically, in particular, with regard to component parts having the same reference numerals, in general, reference may also be made to the figures and/or to the description of the other exemplary embodiments, in particular, of FIGS. 1 and 2. To distinguish the exemplary embodiments, the letter, a, follows the reference numerals of the exemplary embodiment in FIGS. 1 and 2. In the exemplary embodiments of FIGS. 3 and 4, the letter, a, is replaced by the letters, b through c.

FIG. 3 shows an alternative embodiment of a heating device 32b. Heating device 32b includes a valve unit 18b. Valve unit 18b is configured to mix a fluid in a fluid discharge line 14b with fluid from a fluid supply line 12b, upstream from an outlet 20b. Valve unit 18b includes a bypass valve 28b, which is connected fluidically in parallel with a heating unit 10b. A first sensor 60b, which takes the form of a flow rate sensor, and a main valve 68b, are situated fluidically upstream from a branching-off point 70b from fluid supply line 12b in a bypass line 72b connected to bypass valve 28b.

FIG. 4 shows a further alternative embodiment of a heating device 32c. Heating device 32c includes a valve unit 18c. Valve unit 18c is configured to mix a fluid in a fluid discharge line 14c with fluid from a fluid supply line 12c, upstream from an outlet 20c. Valve unit 18c includes a mixing valve 30c, which is situated fluidically in fluid discharge line 14c. A first sensor 60c, which takes the form of a flow rate sensor, and a main valve 68c, are situated fluidically upstream from a branching-off point 70c from fluid supply line 12c in a bypass line 72c connected to mixing valve 30c.

What is claimed is:

1. A heating device, comprising:

at least one heater configured to heat at least one fluid; at least one fluid supply line which supplies the at least one fluid to the at least one heater for heating; at least one fluid discharge line which discharges the at least one fluid from the at least one heater after the heating; a control and/or regulator which operates the at least one heater in a pulsed manner in at least one operating state to set a particular temperature; and a valve unit which mixes the at least one fluid in the fluid discharge line with fluid from the fluid supply line, upstream from an outlet, wherein the control and/or regulator is configured to control the valve unit at least substantially synchronously with a pulsed operation of the at least one heater by generating and/or outputting a control pulse for controlling the valve unit simultaneously to generating and/or outputting a control pulse for controlling the at least one heater.

2. The heating device as recited in claim 1, wherein the control and/or regulator is configured to control the valve unit so that the at least one fluid has an at least substantially uniform outlet temperature.

3. The heating device as recited in claim 1, wherein the control and/or regulator is configured to increase a flow rate of fluid through the valve unit during the pulsed operation, in response to increasing heating power of the at least one heater.

4. The heating device as recited in claim 1, wherein the control and/or regulator is configured to decrease a flow rate

of fluid through the valve unit during the pulsed operation, in response to decreasing heating power of the at least one heater.

5. The heating device as recited in claim 1, wherein the valve unit includes at least one bypass valve, which is situated fluidically in parallel with the at least one heater.

6. The heating device as recited in claim 1, wherein the valve unit includes at least one mixing valve, which is situated fluidically in the fluid discharge line.

7. The heating device as recited in claim 1, wherein the control and/or regulator is configured to operate the at least one heater in a pulsed manner, such that the at least one fluid is heated to a temperature, which lies above a selected outlet temperature of the at least one fluid.

8. A continuous-flow heater, including at least one heating device, the at least one heating device comprising:

at least one heater configured to heat at least one fluid; at least one fluid supply line which supplies the at least one fluid to the at least one heater for heating; at least one fluid discharge line which discharges the at least one fluid from the at least one heater after the heating;

a control and/or regulator which operates the at least one heater in a pulsed manner in at least one operating state to set a particular temperature; and

a valve unit which mixes the at least one fluid in the fluid discharge line with fluid from the fluid supply line, upstream from an outlet,

wherein the control and/or regulator is configured to control the valve unit at least substantially synchronously with a pulsed operation of the at least one heater by generating and/or outputting a control pulse for controlling the valve unit simultaneously to generating and/or outputting a control pulse for controlling the at least one heater.

9. A method for operating a heating device, the heating device including at least one heater which is configured to heat at least one fluid, at least one fluid supply line which supplies the at least one fluid to the at least one heater for heating, at least one fluid discharge line which discharges the at least one fluid from the at least one heater after the heating, and a control and/or regulator which is configured to operate the heater in an at least partially pulsed manner, in at least one operating state, in order to set a particular temperature, the method comprising:

mixing the at least one fluid in the fluid discharge line with fluid from the fluid supply line, upstream from an outlet,

wherein the control and/or regulator is configured to control a valve unit at least substantially synchronously with a pulsed operation of the at least one heater by generating and/or outputting a control pulse for controlling the valve unit simultaneously to generating and/or outputting a control pulse for controlling the at least one heater.
